DRAFT AND BUFFING GEAR

Harvey J. Lounsbury, Glen Ellyn, Ill., assignor to
W. H. Miner, Inc., Chicago, Ill., a corporation
of Delaware

Application March 18, 1933, Serial No. 661,794

4 Claims. (Cl. 213—9)

This invention relates to improvements in draft and buffing gears for mine cars.

One object of the invention is to provide a combined draft and buffing gear especially adapted for mine cars and designed to cooperate with a coupler of the automatic type.

A more specific object of the invention is to provide a gear, of the character described in the preceding paragraph, including shock absorbing means adapted to be actuated in both draft and buff, wherein the buffing forces are transmitted to the shock absorbing means through buffing heads and the draft forces are transmitted to at least part of said shock absorbing means by an automatic coupler member, which is yieldingly held in coupling position and centered by additional shock absorbing means, which is also utilized to absorb buffing shocks.

Other objects of the invention will more clearly appear from the description and claims hereinafter following.

In the drawing, forming a part of this specification, Figure 1 is a part plan and part horizontal sectional view of one end of a mine car, broken away, illustrating my improvements in connection therewith. Figure 2 is an elevational view, partly broken away, of the structure illustrated in Figure 1. And Figure 3 is a vertical sectional view, corresponding substantially to the line 3—3 of Figure 2.

In said drawing, 10 indicates one end of a mine car, 11 the vertical end wall, 12 the floor, and 113 an angle bar member connecting the end wall 11 to the floor 12 and forming, in effect, the end sill member of the car.

My improved combined draft and buffing gear comprises broadly a supporting casing A; a pair of buffing heads B—B; a draft beam C; a coupler D; combined draft and buffing springs E—E; buffing springs F—F; combined coupler centering and buffing springs G—G; and a connecting pin H.

The supporting casing A is secured to the end wall 11 of the car and comprises a platelike member 13 having spaced, outwardly projecting, top and bottom flanges 14—14 and spaced, vertical side flanges 15—15 connecting the top and bottom flanges. The top flange 14 is spaced from the upper edge of the plate 13 and both of the side flanges 15—15 are spaced laterally inwardly from the vertical end edges of said plate. At the forward ends, the vertical side flanges 15—15 are inturned, as indicated at 16—16 in Figure 1, thereby providing front stop shoulders for the buffing heads B—B. Additional stops for the

buffing heads B—B are provided by a pair of retaining members 17—17 disposed between the top and bottom flanges 14—14 of the casing A laterally inwardly of the buffing heads B—B. Each retaining member 17 comprises a vertical section 18 having outwardly projecting top and bottom flanges 19—19 by which the retaining member is secured to the top and bottom flanges 14—14 of the casing A. At the outer end, the section 18 is offset so as to provide a stop shoulder 20, which is arranged in transverse alignment with the stop shoulder 16. Between the retaining members 17—17, the top and bottom flanges 14—14 of the casing A are recessed, as indicated at 21—21 in Figures 1 and 3.

The buffing heads B—B are arranged at opposite sides of the end of the car and are slidably supported by the casing A. The two buffing heads B—B are of the same design, each being in the form of a cap open at the rear end and having a transverse front wall 22 closing the front end. The front wall 22 is thickened, as clearly shown in Figure 1, and presents a transversely curved, outer buffing face 23, which cooperates with a similar buffing head B of the adjacent car. At the inner end, each buffing head B is provided with laterally outwardly projecting flanges 24—24 at opposite sides thereof, which engage in back of the stop shoulders 16 and 20 at the corresponding side of the casing A, thereby limiting outward movement of the buffing head B and holding the same assembled with the casing.

The draft beam C is in the form of a casting having top and bottom flanges 25—25 connected by vertical webs 26—26 at opposite sides thereof. An opening 27 is thus provided at the center of the draft beam for a purpose hereinafter described. The vertical webs 26—26 are of the horizontal section shown in Figure 1 and have their outer end portions rearwardly offset, as shown, to provide spring seats 28—28 at opposite ends of the draft beam C. The top and bottom flanges 25—25 are widened at the center of the beam C, as indicated at 29—29, to provide guide members for the stem of the coupler D, as hereinafter pointed out. The lower enlargement 29 projects beyond the upper enlargement and has a downwardly offset ledge section 30 at the extremity thereof, which engages beneath the head of the coupler D so as to properly support the same in all positions of the coupler.

The coupler D is of the automatic type and comprises a head member 31 having a reduced stem 32 rearwardly projecting therefrom. The

head member 31 presents rearwardly facing, transverse shoulders 33-33 at opposite sides of the stem 32, which shoulders form front abutments for the combined coupler centering and 5 buffering springs G-G. The coupler stem 32 is provided with a longitudinally extending slot 34 adapted to accommodate the connecting pin H.

The connecting pin H is headed at the upper end, as most clearly shown in Figure 3, and extends through vertically aligned openings 35-35 in the top and bottom flanges 26-26 of the draft beam C and through the slot 34 of the coupler stem 32, thereby pivotally connecting the coupler D to the draft beam C and also permitting inward movement of the coupler to a limited extent with respect to said draft beam.

The combined draft and buffering springs E-E are interposed between the outer end walls 22-22 of the buffering heads B-B and the spring seats 20 28-28 at opposite ends of the draft beam C, the inner faces of the walls 22-22 of the buffering heads being provided with seats 135-135 for the outer ends of the springs E-E.

The buffering springs F-F are disposed at opposite sides of the mechanism laterally outwardly of the springs E-E and have their front and rear ends bearing respectively on the inner sides of the walls 22-22 of the buffering heads B-B and on the front face of the plate 13.

30 The combined coupler centering and buffering springs G-G are disposed at opposite sides of the stem 32 of the coupler D and have their front ends bearing on the shoulders 33-33 of the head 31 of the coupler. The rear ends of these springs bear directly on the front face of the plate 13 of the casing A. As will be evident, the springs G-G hold the coupler D projected, as shown in Figure 1, and yieldingly retain the same in centered position.

40 In assembling the mechanism, the draft beam C is inserted through the front end of the casing A before the retaining members 17-17 are applied. The different springs and the buffering heads B-B are then placed in position and the coupler D attached to the draft beam C. With the parts thus assembled, the retaining members 17-17 are applied and riveted to the top and bottom flanges 14-14 of the casing A, thereby holding all of the parts assembled through engagement of the stop shoulders 20-20 of said retaining members with the corresponding flanges 24-24 of the buffering heads B-B.

The operation of my improved draft and buffering gear is as follows: Upon a draft force being applied to the coupler D, the draft beam C is pulled forwardly, thereby compressing the springs E-E against the buffering heads B-B, which are held stationary at that time. As will be evident, when a train of cars is rounding a curve, the couplers D-D thereof will be permitted to swing laterally by means of the pivotal connection thereof with the corresponding draft beams. This swinging movement is yieldingly resisted by the combined centering and buffering springs G-G, which serve to return the couplers to centered position.

During a buffering action, the buffering heads B-B and the coupler D will be forced inwardly toward the end of the car by the corresponding buffering heads and coupler of the adjacent car. During this action, all of the springs E-E and F-F will be compressed against the end of the car, the springs E-E being compressed against the draft beam C, which abuts the plate 13 of the casing A, and the springs F-F being compressed di-

rectly against this plate. The springs G-G, which cooperate with the coupler D during this action, are compressed directly against the plate 13, the necessary inward movement of the coupler D being permitted by the slot and pin connection between the coupler stem 32 and draft beam C.

I have herein shown and described what I now consider the preferred manner of carrying out my invention, but the same is merely illustrative and I contemplate all changes and modifications that come within the scope of the claims appended hereto.

I claim:

1. In a draft and buffering gear for mine cars, the combination with a supporting member fixed to the end of the car; of a pair of buffering heads at opposite sides of the car slidably supported on said member for movement inwardly toward the end of the car, said heads being engageable with similar heads on an adjacent car; a transversely disposed draft beam inwardly of said buffering heads, said beam normally bearing on the end of the car and being slidably supported on said member for movement outwardly away from the car; means for limiting outward movement of said buffering heads; shock absorbing springs interposed between said buffering heads and draft beam; a coupler having a shank; a lost motion connection between said shank and the draft beam, permitting inward movement of the coupler to an extent at least as great as the inward movement of the buffering heads; and springs opposing inward movement of the coupler, said springs bearing at opposite ends on said coupler and supporting member respectively.

2. In a draft and buffering gear for mine cars, the combination with a supporting casing fixed to the end of the car, said casing having a rear abutment wall and outer limiting stop shoulders thereon; of a transverse draft beam slidably supported in said casing for movement away from the end of the car, said beam normally bearing on said abutment wall; a central coupler having a head and a shank, said shank having a sliding swiveled connection with the beam, said sliding swiveled connection permitting movement of said head with respect to the beam in a direction inwardly toward the car; a pair of buffering caps at opposite sides of said coupler slidably supported on said casing for inward movement toward the end of the car to an extent equal to the inward movement of the coupler and limited against outward movement by said shoulders of the casing; springs bearing at the inner and outer ends respectively on said draft beam and buffering caps, said springs opposing relative movement of the caps and beam; and additional springs at opposite sides of the coupler stem having their inner and outer ends bearing respectively on said abutment wall and the coupler head for holding said coupler head yieldingly centered and projected for engagement with a similar coupler head of an adjacent car.

3. In a draft and buffering gear for mine cars, the combination with a draft beam disposed transversely of the end of the car, movable outwardly away from the end of the car and normally held against movement inwardly of said car; of a coupler having a head and a stem rearwardly projecting from the head, said head having rearwardly facing spring abutment shoulders at opposite sides thereof, said stem being longitudinally slotted; a pivot pin connecting the coupler stem to said beam, said pin being fixed to

- the beam and having pivotal and sliding movement within the slot of the coupler stem; springs at opposite sides of the coupler stem, the rear ends of said springs having bearing engagement
 5 with a fixed support on said car and the front ends of said springs bearing on the abutment shoulders of the coupler head; inwardly movable buffering heads mounted on the car at opposite sides of the coupler head; and shock absorbing
 10 means yieldingly opposing inward movement of the buffering heads and outward movement of said draft beam.
4. In a draft and buffering gear for mine cars, the combination with a supporting casing fixed to the end of the car, said casing having a rear abutment wall and outer stop shoulders; of a pair of sliding buffering caps at opposite sides of said casing having their inner ends telescoped within the casing; a pair of springs interposed
 15 between the buffering caps and the abutment wall of the casing and having their front and rear ends bearing respectively on said caps and wall, said caps having their outward movement limited by stop shoulders on the casing; a transversely
 20 disposed draft beam inwardly of the buffering caps, said beam having its opposite ends disposed inwardly of said springs, said beam normally bearing on the rear abutment wall of the casing and being supported for sliding movement outwardly away from the end of the car; a pair of springs at opposite ends of said beam, said springs having their outer ends bearing on the buffering caps and their inner ends bearing on said beam; a coupler midway between said buffering caps, said coupler having a head and stem, said head having rear abutment shoulders at opposite sides; a lost motion connection between said stem and draft beam, said lost motion connection permitting limited outward movement of the coupler with respect to the draft beam; and springs at opposite sides of the coupler stem yieldingly opposing inward movement of the coupler with respect to said beam, said springs having their front ends bearing on the shoulders of the coupler head and their rear ends bearing on said abutment wall of the casing.
